INDIVIDUALLY ILLUMINATED INSTRUMENT
CASING

Maximilian Klein, Sellersville, and William E. Pfeffer, South Perkasie, Pa., assignors to United States Gauge Company, Sellersville, Pa., a corporation of Pennsylvania

Application November 29, 1938, Serial No. 243,046

9 Claims. (Cl. 249—2.1)

The present invention relates to novel casing structures for individually illuminated indicating instruments.

Indicating instruments, usually, are mounted on an instrument board in position to be viewed by an operator seated or otherwise stationed in front of the instrument board. It is often difficult from the operator's position to read such instruments, due to improper lighting of the dial of the instrument. Furthermore, when such instruments are mounted, particularly in the dashboards of automobiles, aeroplanes and the like, where the instrument must be read at night, it has been impossible to adequately illuminate the dial and pointers so that a quick glance will enable a reading of the instrument and eliminate undesired glare.

Under present illumination practices, when the dials and pointers are sufficiently illuminated the light therefrom casts undesirable shadows in the vehicle or glares in the eyes of the operator so that the view from his seat, through the windshield, is seriously impaired.

It is, accordingly, the primary object of the present invention to provide a novel casing structure for use in a system of individual instrument illumination that permits the ready insertion of a lamp from the front of the instrument and the making of the electrical contacts in the act of inserting the lamp, all electrical conduits being concealed and included in the casing.

A further object of the present invention resides in providing the casing for an illuminated indicia bearing element with means for housing a light bulb and electrical connections whereby the indicia bearing element may be illuminated by directing rays of light into the interior of the element, and across the face of the element, without causing glare.

A further object of the present invention consists in adapting a casing for the mounting of a lens and prism designed to the light rays from the lamp and for supplying the electrical current to the lamp to the casing from the rear of the instrument so that when the lamp is secured in the casing from the front all needed connections are thus made.

Another object of the present invention resides in adapting an instrument casing for the reception of a removable lamp designed for edge illumination and indirect lighting of the indicia bearing elements.

A still further object of the present invention resides in providing a sealed casing adapted to receive a removable lamp, and including wiring, 55

sockets and contacts all built into the casing so that energy for the lamp is supplied through the back of the casing and the lamp may be applied from the front where it is readily accessible.

5 A further object of the present invention resides in housing the electrical conduits, contacts, etc., of an individually illuminated instrument in the instrument casing to protect the same from injury, and to facilitate replacement of the lamp and permit its application from the front of the instrument.

Other objects will appear from this description and the appended claims when read in connection with the attached drawings, wherein:

15 Figure 1 is a plan view of a preferred form of an indicating instrument embodying the present invention;

Figure 2 is a sectional view taken on line 2—2 of Figure 1 and looking in the direction of the 20 arrows;

Figure 3 is a fragmental sectional view taken on line 3—3 of Figure 1;

Figure 4 is a fragmental sectional view taken on line 4—4 of Figure 1;

25 Figure 5 is a detailed view in partial section illustrating the manner of fastening the reflector to the glare shield;

Figure 6 is a plan view of a further modification of the present invention;

30 Figure 7 is a sectional view taken on line 11—11 of Figure 6; and

Figures 8 and 9 are partial sectional views taken on lines 12—12 and 13—13 of Figure 6.

With continued reference to the drawings 35 wherein like reference numerals are employed to designate the same parts throughout the several figures of the drawings, numeral 8 indicates generally, the casing of an indicating instrument of any desired character, such as a suction responsive gauge, a pressure gauge; a speedometer, a clock or the like.

40 Casing 8 comprises a cup-shaped body 9, preferably of "Bakelite" or the like; having the usual annular cover glass mounting recesses 10, and recess 11 for reception of the pointer actuation mechanism (not shown). An aperture 12 in body 9, permits connection of said mechanism to its actuating medium, while apertures 13 receive screws (not shown) for securing the mechanism in casing 8. Casing 8 is provided with outwardly protruding ears 14 having apertures 15 therein, to receive elements 16 for mounting the instrument on a supporting structure. Elements 16 comprise internally threaded sleeves having one end 17 riveted over the shoulder 18 provided

by the enlarged end of apertures 15, and a split, automatically locking, hexagonal head 19 overlapping the under face of ears 14.

To adapt casing 8 for illumination purposes, body 9 is provided with a rearwardly extending boss 21 which is formed to provide a suitable electrical socket 22. Socket 22 comprises an outer sleeve-like terminal member 23, embedded in boss 21, and a centrally positioned rod-like terminal member 24, embedded in boss 16 in spaced relation to member 23. Member 23 has an annular groove 25 therein designed to cooperate with a portion of an electrical plug (not shown) which is connected to a suitable source of electrical power. Member 24 is provided with a bore 26 extending part way therethrough designed to receive a mating portion of the above-mentioned electrical plug.

A secondary contact plate 27 on the interior wall 28 of body 9 is connected to member 24 by means of a screw 28 which passes through a suitable aperture in body 9 and is threaded into member 24. A similar secondary contact plate 29 is connected to member 23 by means of a screw 28' in exactly the same manner.

Body 9 is also provided at one side with an elongated boss 31. Boss 31 is hollowed out to house the lamp and provide a bulb-socket 32 therefor.

Socket 32 is connected to socket 22 by an electrical conduit 33. Conduit 33 may take any desired form but preferably consists of an electric wire 34 having suitable insulation 35 therearound encased in a flexible metal sheath 36. One end of wire 34 is connected to contact plate 27 and the corresponding end of sheathing 36 is connected to contact plate 29.

The sheathing 36 at the end of conduit 33 remote from socket 22 is cut back to provide a portion 21 which is not severed from the remainder of the sheathing. The exposed insulation 35 is removed from wire 34 an appreciable distance from the joint between the portion 37 and the remainder of sheathing 36. The bared end 38 of wire 34 is then passed through a suitable aperture 39 in the casing into bore 41 in boss 31. Bore 41 extends the whole length of boss 31 and at its upper end is provided with an enlargement 42, the purpose of which will presently appear.

End 38 of wire 34 is soldered in loop 43 of conduit 44 which is supported by a concentric, insulating, ring-shaped, sleeve 45 fitted snugly in bore 41. Suitable arms 46 passing through apertures 47 of sleeve 45 serve to connect conduit 44 to sleeve 45. The upper end of conduit 44 is provided with an annular socket contact member 49 which engages end 48 of sleeve 45. Sleeve 45, therefore, serves to back-up contact 49 and prevents downward bending of contact 49 in use. Contact 49 has a central aperture 51 therein. The purpose of contact 49 will be herein-after pointed out in detail.

The portion 37 of sheathing 36 is soldered to one end of a conduit member 53 which passes through a suitable passage 54 in body 9 into bore 41 and up the wall of bore 41 in a groove 55 provided for that purpose. A similar groove 56 receives the portion of conduit 44 which passes up the wall of bore 41. Conduit 53 is bent over into enlargement 42 and clamped in place by means of an internally threaded metal socket contact ring 57, the purpose of which will presently appear.

Apertures 39 and 54 are preferably formed by

boring through boss 31 and body 9 from the outside of boss 31. The outer ends of the resulting openings are then sealed with suitable cement as at 58. The space around conduits 53 and 58 in apertures 39 and 54 is similarly sealed to render the casing pressure-tight and to secure the electrical conduits in place.

A suitable miniature light bulb 59, preferably of three volt capacity, is inserted through socket 32 of boss 31 and makes contact with contact ring 49 at 61, and with contact ring 57 through metal protecting cap 62 at 63. Cap 62 is screwed into contact ring 57 with sufficient pressure to retain bulb 59 in place and assure good electrical connections with the socket contacts.

The contact 49 is the live contact and contact 57 is the return or ground contact. Consequently, the electrical plug from the power source is so designed that the current passes to member 24 of socket 22, contact plate 27, through wire 34, conduit 44, contact 49, contact 61 of bulb 59 and returns from contact 63 of bulb 59 through cap 62, to contact 57, conduit 53, sheathing 36, contact plate 29, member 25 to the return line of the power source.

Body 9, adjacent the lower end of sleeve 45, is provided with a wedge-shaped aperture 66 (Figures 1 and 5), the upper edge of which coincides with the bottom of sleeve 45. The smaller end of aperture 66 intersects bore 41 while the larger end intersects recess 11 of body 9. A wedge-shaped prism 68 corresponding in shape to aperture 66 is disposed in the aperture with its smaller end protruding into and extending slightly more than half way across bore 41. Prism 68 provides an external totally reflecting surface 69 and is held in place by a suitable cement, such as "Glyptol" lacquer. Reflecting surface 69 is of arcuate shape in plan and slopes inwardly from top to bottom at an angle of 45° so that the light rays from bulb 59 will undergo total reflection and pass through prism 68 at right angles to the axis of bore 41.

A bull's eye lens 70 is preferably secured by "Glyptol" lacquer in the lower end of sleeve 45, so as to rest upon the upper surface of prism 68. Lens 70 is so designed that the normally divergent light rays from bulb 59 will be refracted so as to leave the exit face of lens 70 in a direction paralleling the axis of bore 41.

Body 9 is also provided with a shallow annular shoulder 71 which is designed to receive a corrugated metal reflector 72. Reflector 72 is preferably flexible, yet rigid enough to retain its position when placed on shoulder 71. The ends 73 of reflector 72 are fastened at points in alignment with the intersection of the side faces and the exit face of prism 68 by hooking apertures 74 of ring 73 behind corners 74' of a glare shield 75 (Figures 1, 2 and 5). Glare shield 75 is in turn cemented at 76 to the exit face of prism 68 in alignment with the top of a dial 77 carried by indicating mechanism M (Figure 3). Shield 75 prevents direct rays of light from passing from the exit face of prism 68 past the edge of dial 77 to cause a glare.

The illumination of the instrument of Figures 1 to 5 is accomplished in the following manner. Socket 22 is connected to a suitable source of electrical energy and through conduit 33 lights bulb 59 in boss 31. The normally divergent rays of light from bulb 59 pass into the bull's eye lens 70 entering the lens through the convex face and emerging through the flat exit face as parallel

rays in a manner well known in the art. The rays passing through the portion of lens 70 overlying the protruding end of prism 68 enter prism 68. A major portion of these last mentioned rays strike arcuate, total reflecting surface 69 and are bent at right angles and pass radially through prism 68. These radially travelling rays of light spread out in a fan shaped manner to illuminate the indicia bearing element and indicating elements of mechanism M.

For a more detailed disclosure of the system of lighting and bulb 59, reference may be had to copending applications of Maxmilian Klein and William E. Pfeffer entitled "Illuminating indicating instruments," Serial No. 243,045, filed on even date herewith, and "Miniature bulb and socket construction" Serial Nos. 243,047 and 243,048 filed on even date herewith which latter two applications have matured into Patent No. 2,210,764, dated August 6, 1940, and Patent No. 2,190,875, dated February 20, 1940.

A further modification of the invention is disclosed in Figures 6 to 8. In this form of the invention, a casing 9b substantially like that of Figures 1 to 4 is used. As a consequence, the same reference numerals will be used for the identical parts and the detailed description thereof will be omitted.

In this form of the invention, casing 8b, comprises a body 9b designed to receive two indicating mechanisms, for example, an air gauge and a fuel gauge both of which cooperate with a single dial member 110 having suitable scales (not shown) thereon. These gauges are mounted in recess 11 and the bottom wall 28 is provided with two apertures 12 and two sets of apertures 13. Conduit 33 is connected to socket 22 as heretofore described, and the opposite end thereof is passed through an enlarged opening 111 interconnecting space 11 and bore 41b, of boss 31b.

End 38 of wire 34 is soldered to a spring metal contact member 112 which is disposed in groove 56 and end 37 of sheathing 36 is soldered to the bared end of insulated conduit 113 which is disposed in groove 55. The opposite end of conduit 113 is clamped between metal bulb adaptor 114 and an insulating sleeve or ring 115 threaded into adaptor 114. Sleeve 115 encircles metal contact bushing 116 and clamps flange 117 of bushing 116 against insulating washer 118 which is in turn clamped against shoulder 119 of adaptor 114.

The protruding end 121 of bushing 116 extends into bore 41b and is threaded into complementary metal contact bushing 122 and bears upon the edge of the convex surface of bulb's eye lens 70 to clamp lens 70 against shoulder 123 of bushing 122. Bushing 122 extends to a point adjacent the bottom of bore 41b and is internally threaded at 124. A screw 125 having suitable wrench receiving apertures 126 therein is threaded into bushing 122 and secures adaptor 114, washer 118, contact bushing 116, insulating ring 115, contact bushing 122 and lens 70 in proper position in bore 41b. Suitable sealing gaskets 127 are preferably disposed between the end faces of boss 31b and adaptor ring 114 and screw 125 to assure a pressure-tight point at these points. To prevent a short circuit between contact 112 and conduit 113 at their point of jointure with end 38 of wire 34 and portion 37 of sheathing 36, an insulating washer 128 having a radially extending tab 129 is disposed against the lower end face of bushing 122 with tab 129 extending into aperture 111 and overlying the end of conduit 33.

In order that light from bulb 59 may reach 75

prism 68, the wall of bushing 122 adjacent the prism is provided with a peripheral slot 131. The protruding end of prism 68 extends through slot 131 with its reflecting surface 69 located below the flat exit face of lens 70.

Bulb 59 is lighted over the following circuit: from live terminal 24 of socket 22 through plate 27, wire 34, contact 112, contact bushing 122, bulb contact 61, the bulb filament, bulb contact 63, adaptor 114, conduit 113, sheathing 36 to ground or return terminal 23 of socket 22.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A casing for an indicating instrument comprising a cup-shaped body portion having a rear wall and an open face, an electrical socket imbedded in and projecting from the rear wall, electrical conducting means passing from the imbedded portion of said socket through said rear wall to the interior thereof and providing electrical contacts within the interior of the cup-shaped body, means formed in the interior of the peripheral wall of said cup-shaped body adjacent said open face for receiving a cover glass and a cover glass securing ring, a peripheral shoulder in said last mentioned wall adjacent said means for receiving a light reflecting element, a split, annular reflecting element on said shoulder having its two ends in spaced relation, an external protuberance formed on said body at a point adjacent said spaced ends of said reflector and having a bore therein, a passageway through said peripheral wall interconnecting the interior of said cup-shaped body and said bore, said passageway having one end located in the space between the ends of said reflector and providing passage for light rays from said bore to the interior of said cup-shaped body, a lamp socket in said protuberance, electrical conduit means within the interior of said body interconnecting said contacts in the interior of said cup-shaped body and said lamp socket and passing through the common wall of said body and protuberance, and means preventing the passage of air through the bore of said protuberance between the interior of said body and the atmosphere.

2. The combination defined in claim 1 wherein in said bore is provided with a pair of longitudinally extending grooves for receiving said electrical conduits; an insulating sleeve for retaining the conduits in said grooves, and a condensing lens for paralleling light rays before they enter said passageway.

3. An instrument casing designed for individual illumination comprising an integral cup-shaped body and hollow boss having a common wall, said boss having a front end adjacent the open or front end of the cup-shaped body, and the hollow therein being provided by a longitudinal bore open at the front end; a plurality of spaced contacts for receiving a lamp inserted from the front of said casing with its head in said bore, whereby light from said lamp will be

directed into the bore; a condensing lens below said contacts and occupying substantially the cross-sectional area of said bore; transparent means below said lens providing a light passageway between said bore and the interior of said cup-shaped body and for reflecting light from said lens into said interior; an electrical connection on the rear wall of said body; and electrical conducting means between said contacts and said connection, said conducting means lying adjacent the walls of said bore and passing through said common wall below said transparent means, thence through the interior of said body to the rear wall and said connection.

4. The combination defined in claim 3 wherein in said transparent means and said conducting means are sealed where they pass through said common wall whereby the cup-shaped body interior is sealed against leaks through said bore.

5. The combination defined in claim 3 wherein in a single passageway for said reflecting means and said conducting means is provided in said common wall, and said bore is provided with means for sealing said bore and communicating cup-shaped body interior against air leakage.

6. An instrument casing for use in individually illuminated indicating or like instrument comprising a cup-shaped non-conducting body having an open face and a rear wall, an electrical socket embedded in the rear wall and projecting from the back thereof, electrical contacts on the inner surface of said rear wall, extending through a portion of said wall and connected to the imbedded part of said socket, a boss formed on the peripheral wall of said body and having a bore therein, lamp socket contacts in said bore, a pair of relatively small passages through the peripheral wall of said body interconnecting the interior of the body and said bore, electrical conduits extending through said passages and interconnecting said contacts on said rear wall and said lamp socket contacts, means sealing said passages against leakage of air therethrough, and means for transmitting light from said bore through said peripheral wall and into the interior of said body.

7. An instrument casing for use in individually illuminated indicating or like instruments, comprising a non-conducting cup-shaped body having an open face and a rear wall, an electrical socket embedded in the rear wall and projecting from the back thereof for connection to a source of electrical energy, means connected to and passing from the imbedded portion of said socket to the interior of the rear wall to provide contacts on the inner surface of said rear wall, a boss formed on the peripheral wall of said body and having a bore separated from the interior of the casing by said wall, lamp socket contacts in said bore, at least one passage through the peripheral wall of said body interconnecting the interior of the body and said bore, an electrical conduit extending through said passage and interconnecting said contacts on said rear wall and said lamp socket contacts, means for receiving a lamp in said bore so as to engage said contacts, means for transmitting light from said lamp through said peripheral wall and into the interior of said body, and means preventing the leakage of air to or from the interior of said casing through said bore to the atmosphere.

8. An individually illuminated casing designed to accommodate an indicating instrument for use with a dial member, comprising a cup-shaped body having a rear wall and providing a space for an indicating instrument, a socket member accessible from the exterior of said rear wall for connection to a source of electrical energy, electrical conductors connected to said socket and providing contacts on the interior of said rear wall, a boss on the peripheral wall of said body providing a lamp housing and socket, means forming a light passageway through said peripheral wall from said lamp housing to said space, and an electrical conduit interconnecting said contacts and said lamp socket passing through said last-mentioned passage, wherein said lamp housing and socket comprise a bore in said boss, a sleeve having internal threads in its opposite ends and a notch in its peripheral wall, a pair of grooves in the wall of said bore for receiving electrical conduits, an electrical conduit in each of said grooves one of which makes electrical contact with said sleeve, a second sleeve having an externally threaded portion for engagement with one end of said first mentioned sleeve and forming an electrical contact for a lamp, an insulating ring snugly fitting around said second sleeve and having an external threaded portion, a flange on said second sleeve engaging an end face of said ring, a metal adapter screw-threadedly engaged with said ring to secure said other conduit therebetween and having a threaded aperture of smaller diameter at the end opposite that threadedly engaged with said ring, an insulating washer between the flanged end of said second sleeve and the portion of said adapter surrounding said threaded aperture of smaller size, a lamp freely received in said threaded aperture of smaller size having an electrical contact engaging said second sleeve, a metallic protecting cap threaded into said smaller sized aperture and engaging the end of said lamp to clamp the lamp in the socket and complete the circuit to said adapter and other conduit and a headed screw-threaded fastener engaging the internal thread of the other end of said first-mentioned sleeve to secure the lamp housing and socket elements in place in said bore.

9. A casing for an instrument designed for individual illumination, comprising a cup-like body having a hollow boss projecting laterally of said body at the edge of the open end thereof and adapted to receive an electric bulb at one end portion; means in the wall of said body between the inside of said cup and said hollow boss for reflecting light rays emitted by the lamp from said hollow boss to the inside of said body; electric lamp contacts in the hollow of said boss near the lamp receiving end portion; light condensing means between said reflecting means and said lamp contacts; an electric socket in the back wall of the casing, and conductors on the inside of said casing and connected to said socket and contacts, said conductors passing from the inside of said body to the inside of said boss at a point below said reflecting means and thence along the inner wall of said hollow boss, whereby they do not interfere with the passage of light through said means.
